UNITED STATES PATENT OFFICE.

JAMES C. RUSSELL, OF PITTSBURGH, PENNSYLVANIA.

TREATING OF METAL ARTICLES.

1,008,674.

Specification of Letters Patent. Patented Nov. 14, 1911.

Application filed December 5, 1910. Serial No. 595,814.

To all whom it may concern:

Be it known that I, JAMES C. RUSSELL, a resident of Pittsburgh, in the county of Allegheny and State of Pennsylvania, have 5 invented a new and useful Improvement in Treating of Metal Articles; and I do hereby declare the following to be a full, clear, and exact description thereof.

My invention relates to the treating of 10 metal articles, such as steel railroad rails, bars, plates, channels and other similar articles, and has special reference to soft steel or low carbon articles.

The object of my invention is to provide 15 a cheap, simple and efficient method for treating a soft or low carbon steel article, which will enable such article to be hardened by such treatment so that it may be used for the purpose for which it is desired, such 20 as in the treatment of rails and other articles to take the place of a high carbon steel article.

To these ends my invention consists, generally stated, in the novel method of treating 25 metal articles, as hereinafter more specifically set forth and described, and particularly pointed out in the claims.

To enable others skilled in the art to which 30 my invention appertains to practice and use my improved method of treating metal articles, I will describe the same more fully, referring to the accompanying drawings, in which—

Figure 1 is a side elevation of an apparatus for carrying out my improved method for treating metal articles. Fig. 2 is an enlarged side view of one of the troughs employed. Fig. 3 is a horizontal section on the line 3—3, Fig. 2, looking in the direction of the arrows. Fig. 4 is an enlarged cross-section on the line 4—4, Fig. 2. Fig. 5 is an enlarged cross-section on the line 5—5, Fig. 2 showing some of the parts in full lines and looking in the direction of the 45 arrow. Fig. 6 is a sectional plan view on the line 6—6, Fig. 1, looking in the direction of the arrows. Fig. 7 is a sectional side view on the line 7—7, Fig. 3. Fig. 8 is a detailed view of one of the traps employed. Fig. 9 is a side elevation of rolls employed in the troughs for use in treating different articles and different sizes of same.

Like symbols of reference herein indicate like parts in each of the figures of the drawing.

55

As illustrated in the drawings, the apparatus for carrying out my invention is shown at A, and preferably consists of two troughs 1 and 2, which are separate from each other, and between which is the reheating furnace 60 3, through which the articles are passed from the trough 1 to the trough 2. The troughs 1 and 2 are provided with a bottom 4 therein which is set at an incline and is connected to the sides 5 of said troughs in 65 any suitable manner. An opening 6 is formed in the sides of said troughs 1 and 2 and at the downward side of the inclined bottoms 4 therein, which openings lead from said troughs to a drain trough 7 at that side 70 of said troughs, and the size of such openings is regulated or is closed by means of an adjustable trap plate 8 mounted on such sides by the bolts 8'. An overflow box 9 is formed at the front end of each of the drain troughs 75 7, and from the same a pipe (not shown) can be connected for draining any water collected in said troughs when desired. An opening 10 is formed in the rear end of the drain troughs 7, which is opened and closed 80 by means of an adjustable gate 10' supported by bolts 11 on said ends and mounted in slots 11' within such gate to regulate the height of the same.

Within the troughs 1 and 2 are a series 85 of upper and lower rolls 12 and 13 which are journaled in the sides 5 in said troughs in the usual manner by their shafts 12' and the upper and lower rolls at the entering or front ends of said troughs are placed in a 90 vertical line with each other, while the balance of said rolls are staggered with each other. The upper rolls 12 are provided with a flat face 12'' thereon and the lower rolls 13 are provided with flanges 13' thereon for 95 forming a groove 13'' between such flanges, and these rolls are all revolved in the same direction as shown by the arrows in Fig. 2, by means of suitable gearing (not shown) connected to the shafts 12' of the same, 100 which gearing is connected in any suitable manner through suitable devices to the usual source of power to operate such rolls thereby. Extending between the sides 5 of

the troughs 1 and 2 is an inner trough 14 which is preferably formed by means of side plates 15, which are connected at their bottom edges to the bottom 4 and one of the 5 sides 5, and at their upper ends to the top plate 16 to form an air tight trough and confine any flames from the oil therein, as hereinafter described. At the front and rear of the troughs 1 and 2 and within the 10 same is a vertical wall 17 which is adapted to form an overflow compartment 18 in said troughs between said walls and the end walls 18' of said troughs, and between the said front and end wall and leading from the 15 lower end of the compartments 18 is a drain pipe 19. Within an opening 20' in each of the walls 17 and 18 of the troughs 1 and 2 is a trap or valve device 20 which is composed of the gate or outer valve block 21 adapted to 20 slide in the grooves 21' by its flanges 21" in said walls, and the pivoted inner valve block 22 located under said block and fitting in said opening, such inner valve block having the opening 22' in the same of the shape 25 of the article such as the head and web of the rail passing through the same and being adapted to adjust itself in said opening 20', such as by the rail passing through the same as hereinafter described, so that it and such 30 rail will maintain a horizontal position for the passing of said rail through said troughs.

Within the troughs 1 and 2 are the rollers 35 23 which are located between the front and intermediate rolls 12 and 13 and at the rear of the troughs, and are vertically mounted and provided with flanged portions 23' above their body portions 23''. These rollers 23 are journaled in bearings 24' within 40 the troughs 1 and 2, and are slidably mounted on the rods 24 extending through said bearings and through the side walls 5 of said troughs and side plates 15 of the trough 14, while such bearings are adapted 45 to be adjusted to any desired position with respect to the openings between said rollers by bolts 25 bearing against said bearings and extending through said walls and plates.

50 Within each of the troughs 1 and 2 is a bath 26 of a cooling medium, for extending entirely around the article to be treated, the former being composed of oil and water, and the latter being only of water. Water 55 for each of these baths enters the troughs 1 and 2 by means of pipes 27 entering through the end walls 17 and 18' of said troughs, which pipes lie parallel with the side of the head on the rail to be heated, and 60 such pipes are provided with perforations or openings 27' therein and at intervals throughout the lengths of the same within said troughs for the entrance of water in said troughs to said baths. Entering 65 through the walls 17 and 18' on the front

end of the trough 1 and below the water pipes 27 are the oil pipes 28 which open into said troughs and within the bath 26 for forming part of said bath.

The reheating furnace 3 which is located 70 between the troughs 1 and 2 is provided with a reheating chamber 29 within the same which extends entirely through said furnace, and extending within said chamber and above and below the same are the 75 idle rollers 30 for bearing against the top and bottom of the article reheated therein, and passing from the trough 1 to the trough 2 as hereinafter described. Located centrally of the furnace 3 and at intervals 80 throughout its length are a series of gas pipes 31 which extend through the bottom of said furnace and open into the chamber 29, such pipes being provided at the upper ends of the same and within said chamber 85 with T-burners 32 extending out from the sides of the same. Directly opposite to each of the T-burners 32 are a series of gas pipes 33 which extend through the sides of said furnace and open into the chamber 29. 90

In the use and operation of the apparatus A in the treating of metal articles under my invention and in connection with an article, such as the ordinary soft steel railroad rail, as shown, is as follows: After the finished rail *a* leaves the usual devices for sawing the same into proper lengths and while in a heated condition it is passed in any suitable manner through the opening 20' in the wall 18' of the trough 1, over the compartment 18 therein and through the opening 20' in the wall 17 into the bath 26 in the inner trough 14 of said trough. As the front or entering end of the rail *a* thus enters and passes into the trough 1 it will 100 strike against the blocks 21 of the traps 20 in the walls 18' and 17 and raise the same in their guides 21' in said walls, so that such rail will enter the pivoted blocks 22 in such walls and maintain the same to a horizontal 105 position in the openings 20' in said walls as well as prevent the bath 26 in such trough from escaping into the compartments 18 or any air entering through the walls 18 during the passing of the rail into and through the trough 1. After the entering end of the rail *a* has passed the walls 18' and 17 and has entered the bath 26 in the trough 1, such bath will completely cover the same 110 and it will be caught by the first two forward rolls 12 and 13, with its head *b* fitting in the groove 13'' in the lower roll 13 and with the bottom of its flange *c* against the flat face 12'' on the upper roll 12. After such rail *a* is so caught by the forward rolls 115 12 and 13, it is drawn forward thereby so that it can pass through and between the rollers 23 in the trough 1, which will allow the flange portions 23' on said rollers to bear 120 against the flange *c* and web *d* of said rail 125 130

and the body portions 23" thereon to bear against the sides of the rail head *b*, and thereby enable such rollers to tend to hold the rail *a* in perfect alinement by assisting 5 the rolls 12 and 13. After the entering end of the rail *a* has passed the rollers 23 it will be caught by the other rolls 12 and 13 in the trough 1 to continue the drawing of 10 said rail through said trough and then such end is caught by the rollers 23 at the rear end of said trough, while at the same time such rail is guided in a straight horizontal line by said rolls and rollers engaging with the head *b*, flange *c* and web *d* of the same, 15 and will keep said rail in its proper finished shape and alinement. After the front or entering end of the rail *a* has passed the rear rollers 23 in the trough 1 it passes through the openings 20' in the rear end 20 walls 17 and 18' of said trough and pivoted blocks 22 in said walls, as well as over the rear compartment 18 and strikes against the gate blocks 21, which will maintain said blocks in their horizontal positions and 25 open up said passageway 20' by said blocks in raising the same in their guides 21' in said walls, so that such rail end after entering the opening 20' in the rear end wall 18' will allow such rail to pass out of said 30 trough. During the passing of the rail *a* through the trough 1 it will be submerged entirely in the bath 26 of oil and the water to harden the same, which bath will be constantly agitated by the movement of the 35 rolls 12 and 13 and rollers 23 within the same, as well as by the passing of the rail through said bath and by the water entering such bath from the pipes 27 located above the oil entrance pipes 28, which will 40 enable such oil to pass up through the water in said bath in seeking its level on account of such oil being of less specific gravity than such water. This will tend to completely envelop the entire rail *a*, and the water from 45 the pipes 27 forced against the head of the rail will tend to displace most of the oil from said head and create a constant agitation of the oil and water around the head, while the web *d* and flange *e* of the rail will 50 be immersed in substantially an oil bath, with some small amount of water from the pipes 27 which creates the agitation around the rail head mixing with the oil around the web and flange of the rail. 55 As the rail *a* thus passes out of the trough 1 it enters the chamber 29 of the reheating furnace 3 and between the rollers 30 therein, where such rail during its passage through said chamber will be reheated by the gas 60 emitting from the pipes 31 and 33 therein against the rail head *b* to reduce the temper of the head of said rail, as well as to burn off any oil remaining on said rail from the oil and water in the bath 26, so that said 65 rail will at once be again subjected to the

water in the bath 26' of the trough 2 to hold the temper at the degree in the same to which it has been drawn by the furnace 3.

The rail *a* in passing out of the chamber 29 of the reheating furnace 3 enters and passes through the trough 2 in like manner, as in the trough 1, and the entire rail is submerged in the water bath in the same, and after the rail has left the troughs 1 and 2 and the traps 20 therein, the gate blocks 21 will drop down in their guides 21' in the walls 17 and 18' of said troughs to close the openings 20' for the rail in said walls and the pivoted blocks 22 to be positioned in said openings for receiving another rail to 80 be treated, while the gate blocks 21 in the inner walls 17 will prevent any oil or water from escaping from the troughs 1 and 2 into the compartments 18, and the inner trough 14 will act to prevent any leakage of the 85 oil or water around the rolls, or supports for the bearings for the rollers and through the sides of the said troughs.

While the rail *a* is thus passing through the troughs 1 and 2 and being treated by the 90 baths 26 in such troughs, any overflowing or escaping of the oil and water from such baths caused by the movement of said rail through the same will pass through the openings 20' in the walls 17 at the front and rear 95 ends of said troughs and into the compartments 18 at such ends, where it can be drawn off by the pipes 19 into a suitable receptacle or be returned to the baths therein, as desired. During this passing of the rail *a* 100 through the troughs 1 and 2, the water in the baths 26 in said troughs is drained therefrom into the drain troughs 7 through the openings 6 in the sides of said troughs 1 and 2, as well as any scale from 105 said rail through the treating of the same by the oil and water and water baths therein, which scale will pass down the inclined bottoms 4 in said troughs and into the troughs 7 through said openings to collect 110 the same, while such water can pass from said drain troughs 7 through the openings 10 at the rear ends of said troughs into a suitable receptacle or be returned to said troughs 1 and 2, as desired. In case of any 115 overflow in the troughs 7, the water therefrom can be passed into the overflow boxes 9 in said troughs and be withdrawn therefrom to a suitable receptacle or be returned to the troughs 1 and 2, as desired, while any scale 120 collected in the troughs 7 can be removed therefrom, as desired.

It will be evident that the troughs 1 and 2 can be of sufficient width to enable two or more rails to be passed through the same at 125 one time, or separate parallel troughs can be used for treating two or more rails at a time, and the reheating furnace can be made to accommodate two or more rails therein for treatment at one time, such as is shown 130

by the two rails in Fig. 6. The reheating furnace can also be provided with the usual pyrometer, which would keep such rail at a uniform heat, and where an article of a 5 lighter weight is used a furnace can be placed in front of the trough 1 to heat article to a uniform temperature before being passed into said trough.

If desired, water pipes 27" can be placed 10 in the trough 1 and above the water pipes 27 therein so that water can be passed from said pipes 27" into the bath 26 therein to further assist in agitating the oil and water composing said bath, and it will be evident 15 that the trough 2 and reheating furnace 3 may be dispensed with in the treatment of certain articles, so that only the single trough 1 with its bath of oil and water will thus be used for treating metal articles, 20 while articles other than rails, such as bars, plates, rods, pipes, shear knives, steel castings and other articles of either high or low carbon can be treated in like manner.

In Fig. 9 there is shown a set of upper 25 and lower vertical rolls 34 and 35 to take the place of the rolls 12 and 13 in the troughs 1 and 2 for the drawing of different sizes of eye beams *e* through said troughs in the treating of the same by different sized 30 passes 34' and 35' on said rolls, and on one side of said rolls the horizontal rollers 36 and 37 are shown in dotted lines for bearing against the flanges on said beams, and the other side of said rolls can be used in 35 the drawing of angle bars by the pass 35' in said rolls, when it is desired to treat the same in said troughs. In case it is desired to draw and treat channel bars *e'*, the side of the rolls 34 and 35 in the rolling of the 40 eye beams *e* can be used.

Various other modifications and changes 45 in carrying out the method or process employed in my improved treating of metal articles may be resorted to, without departing from the spirit of the invention or sacrificing any of its advantages.

It will thus be seen that a very soft tough 50 steel or low carbon steel railroad rail or other metal article, such as one of about three-tenths of one per cent. or four-tenths of one per cent. carbon can be treated so that it will become much harder than before treating and when being so hardened the rail or article is kept in its finished shape 55 and in proper alignment, while a rail so hardened will be kept from breaking under any quick jar or heavy strain, as is common with the high carbon steel rails now in use.

60 It is well known that in the use of oil in the treatment of steel after it is finished, that the article so treated would be of very tough and close grain, which would add to the wear and strength of such article, while 65 the water used with such oil will harden

such article and enable it to be hardened at a higher heat to make it a better article and of a better quality when combined with the oil than the ordinary high carbon article, such as a rail, as the oil seems to have an 70 affinity for the steel by closing up the pores of the same and adding greatly to its strength.

What I claim as my invention and desire to secure by Letters Patent is— 75

1. The process of treating metal articles, consisting in subjecting a heated article simultaneously to the action of a bath composed of two cooling medii, one portion being subjected to the action of oil and another 80 portion being subjected to the action of water by passing the article through said bath and parallel to its surface.

2. The process of treating rails, consisting in subjecting a heated finished rail simultaneously to the action of two cooling medii, the web and flange being subjected to the 85 action of oil and the head being subjected to the action of water.

3. The process of treating metal articles, 90 comprising the step of passing the hot article through a cooling medium bath of oil which surrounds said article, and projecting a stream of water through the oil upon a portion of said article. 95

4. The process of treating metal articles, comprising the steps of passing the hot article through a cooling medium bath of oil which surrounds said article, projecting a 100 stream of water upon a portion of said article, then reheating said article to reduce its hardness, and then passing the article through a cooling medium bath to hold the degree of hardness in said article caused by 105 said reheating.

5. The process of treating metal articles, comprising the steps of passing the hot article through a cooling medium bath of oil which surrounds said article, projecting a stream of water upon a portion of said article, then reheating said article to reduce 110 its hardness, and then passing the article through a cooling medium bath of water to hold the degree of hardness in said article caused by said reheating. 115

6. The process of treating rails, comprising the step of passing the hot finished rail through a cooling medium bath of oil which surrounds said rail, and projecting a stream of water upon the head of the rail. 120

7. The process of treating rails, comprising the steps of passing the hot finished rail through a cooling medium bath of oil which surrounds said rail, projecting a stream of water upon the head of the rail, then reheating said rail to reduce its hardness, and then passing the same through a cooling bath to hold the degree of hardness in said rail caused by said reheating. 125

8. The process of treating rails, compris- 130

ing the steps of passing the hot finished rail through a cooling medium bath of oil and water which surrounds said rail, projecting a stream of water upon the head of the rail, 5 then reheating said rail to reduce its hardness, and then passing the same through a cooling bath of water to hold the degree of hardness in said rail caused by said reheating.

10 9. The process of treating metal articles, comprising the step of passing the hot ar-

15 ticle through a cooling medium bath of oil which surrounds said article, and projecting a stream of water through the oil and against said article.

In testimony whereof, I, the said JAMES C. RUSSELL, have hereunto set my hand.

JAMES C. RUSSELL.
